Attorneys

UNITED STATES PATENT OFFICE.

GEORGE NORRIS CAROTHERS, OF CUTLER, OHIO.

CORK EXTRACTOR.

Application filed December 7, 1921. Serial No. 520,535.

To all whom it may concern:

Be it known that I, GEORGE N. CAROTHERS, a citizen of the United States, residing at Cutler, in the county of Washington and State of Ohio, have invented certain new and useful Improvements in Cork Extractors, of which the following is a specification.

This invention relates to cork pullers; or extractors, of the type embodying pivoted jaws in contra-distinction to the type embodying an inserting screw and the primary objects of the invention are first, to provide, in a cork extractor of the above character, novel means for permitting the independent insertion of the jaws intermediate the cork and the bottle neck, so as to allow the easy and convenient placing of the puller or extractor in position without the likelihood of the cork being pushed within the bottle and second to provide means whereby the jaws can be adjusted within certain limits in relation to each other, whereby corks of different diameters can be readily engaged.

A further object of the invention is the provision of a novel cork extractor or puller embodying a pair of members including gripping jaws for engaging a cork and for insertion between a cork and a bottle neck, said members being associated together in a novel manner, whereby independent movement of the same longitudinally of each other is permitted, so that the jaws can be independently inserted between the bottle neck and cork, the jaws being of novel construction and disposed in relation to each other so as to permit firm grasping of a cork.

With these and other objects in view, the invention consists in the novel construction, arrangement and formation of parts, as will be hereinafter more specifically described, claimed and illustrated in the accompanying drawings, forming a part of this specification, in which drawings:

Figure 1 is a side elevation of the improved tool, showing the jaws in operative engagement with a cork and inserted intermediate the bottle neck and cork.

Figure 2 is a similar view showing one of the members inserted between the cork and bottle neck and the other member in a raised position ready for insertion between the bottle neck and cork.

Figure 3 is a fragmentary edge elevation of the improved tool showing the arrangement of the jaws in relation to each other.

Figure 4 is a detail perspective view of one end of the handle of one of the members showing the bottle cap opener formed thereon and in use, and

Figure 5 is a fragmentary detail elevation of one of the members showing the adjusting slot therein.

Referring to the drawings in detail, wherein similar reference characters designate corresponding parts throughout the several views, the letter A indicates the improved tool which includes the members B and C which are constructed similar to one another, so as to form companion members for the cork pulling or extracting operation.

The member B includes a handle 5, which is preferably formed circular shaped in cross section, so that a convenient grip can be had thereon by the hand of the user. The forward end of the member B has formed thereon the inserting and gripping jaw 6 and the portion of the member intermediate the jaw 6 and the handle 5 is flattened as at 7 for a purpose, which will be herein-after more specifically described. The member C, as stated, is formed similar to the member B and comprises the cylindrical handle 8, the inserting and grasping jaw 9 and the intermediate flattened portion 10. The flattened portions 7 and 10 of the members B and C are adapted to be placed in abutting relation to one another and cross each other as clearly shown in Figure 1 of the drawings. The flattened portion 7 is provided with a longitudinally extending slot 11 to which is adapted to slide a headed rivet 12 carried by the flattened portion 10 of the member C. The headed rivet 12, as shown, is disposed intermediate the ends of the flattened portion 10.

This slot 11 permits the independent longitudinal movement of the members B and C in relation to one another, so that the jaws 9 and 6 can be independently inserted between the cork and the bottle neck, thus facilitating the easy placing of the tool in position without the likelihood of the pushing of the cork within the bottle. The flattened portion 10 of the member C is provided with a cross slot 13 for the rivet 12, which allows a certain adjustment between

the members B and C whereby corks of different sizes can be readily pulled or extracted by the improved tool. The ends of the slot 13 terminate in pockets or notches 5 13' for the reception of the rivet 12. As stated, the rivet 12 is headed and the heads are of a sufficient size to prevent displacement of the rivet from the slot and pockets.

The jaw 9 extends forwardly of and at right 10 angles to the flattened portion 7 and may be slightly bowed longitudinally, as shown in Figures 1 and 2 of the drawings in order to facilitate the insertion thereof in between the cork and the bottle neck. The free 15 terminal of the jaw 9 is preferably pointed as at 14 in order to facilitate the insertion of the jaw between the cork and the bottle neck.

The jaw 6 is formed similar to the jaw 9 20 with the exception that its lower end is terminated in a straight line or is of chisel-like formation, as at 15, but this straight edge may be sharpened in order to allow the insertion thereof between the cork and 25 the bottle neck. This jaw is preferably not pointed in order to permit of a relatively large area of gripping surface to engage the cork.

It is desirable that one handle of the device 30 be provided with a bottle opener and as shown the handle 5 has the face provided with a bottle opener 18 and in Figure 4 is shown the use of this opener. The other handle 8 can also be provided with some tool if desired such as screw driver or the like. The formation of tools, however on the terminals of the handles 5 and 8 is not vital to the invention and can be eliminated if so desired.

In use of the improved cork extractor, the handle 5 of the member B is moved upwardly until the end wall of the slot 11 engages the rivet 12. The lower terminal of the jaw 6 will then be well above the lower 45 terminal of the inserting jaw 9 as clearly shown in Figures 2 and 3 of the drawing. The jaw 9 is then inserted between the bottle neck and cork as clearly shown in Figure 2 of the drawing. When the jaw 9 has been inserted into position the jaw 6 is swung on the rivet 12 until the same comes in between the cork and the bottle neck, at which time the same is forced inwardly between the cork and bottle neck. The handles 5 and 8 are then tightly grasped, and an upward pull and a slight turning or twisting movement is given to the tool, which will effectively extract the cork from the bottle neck.

The formation of the jaws in relation to each other is such as to permit a firm engagement of the cork without mutilating the same in any way whatsoever.

If the cork is of a relatively large size, it is merely necessary to slide the rivet 12

in the cross slot 13 to fit in the inner pocket, which will permit the jaws 9 and 6 to be adjusted further away from each other.

From the foregoing description, it can be seen that an exceptionally simple and durable cork extractor has been provided which embodies a minimum number of parts none of which are subjected to great wear or apt to become broken by rough usage.

Changes in details may be made without departing from the spirit or scope of this invention; but,

I claim:

1. A cork extractor comprising a pair of companion members, each including a handle, a jaw and an intermediate flattened portion, the flattened portions being disposed in abutting relation, one of the jaws being pointed, the other jaw having its free terminal flattened, one of the flattened portions being provided with a longitudinal slot, the other flattened portion having a transverse slot provided with pockets, and a headed rivet fitted in the transverse slot and longitudinal slot and arranged to seat in 90 said pockets.

2. A cork extractor comprising a pair of members engaging one another in crossed relation intermediate their ends and provided with handles to one side of their engaging portions and relatively slender cork gripping end formations at the other side of their engaging portions, and a pivotal connection for said crossed members permitting relative sliding longitudinal movement of one member with respect to the other whereby one gripping end formation may be moved into operative relation to the cork in advance of the other and permitting relative transverse movement of one member with respect to the other, independent of said first mentioned movement, whereby the extractor may be adjusted for gripping relation to different sizes of corks.

3. A cork extractor comprising a pair of crossed members and a pivot connecting said members intermediate their ends, said members, to one side of the pivot provided with operating handles and at the opposite side with relatively slender cork gripping end portions, one of the crossed members provided with a longitudinally extending slot and the other crossed member with a transversely extending slot and pockets at the ends of said last mentioned slot, said pockets extending toward the cork gripping end portion of the crossed member, and said pivot extending through said slots and adapted to seat in either of said pockets, substantially as and for the purpose set forth.

4. A cork extractor comprising a pair of members pivotally connected together intermediate their ends and provided, to one side of the pivotal connection with operating han-

dles, and to the opposite side with cork gripping end formations, the gripping end formations, the gripping and formation of one member being pointed and the companion portion of the other member 5 being of chisel-like formation, substantially as and for the purpose set forth.

5. A cork extractor comprising a pair of members pivotally connected together intermediate their ends and provided, to one 10 side of the pivotal connection with operating handles, and to the opposite side with

cork gripping end formations, the gripping end formation of one member being pointed and the companion portion of the other member being of chisel-like formation, the 15 pivotal connection being such as to permit the member with pointed end formation to be moved into operative relation to the cork independently, and in advance of movement of the member with the chisel-like end formation into operative relation to the cork. 20
